UNITED STATES PATENT OFFICE.

OLIVER GILTNER, OF PORTLAND, OREGON.

BOLT OR SPIKE PULLER.

SPECIFICATION forming part of Letters Patent No. 728,096, dated May 12, 1903.

Application filed March 10, 1903. Serial No. 147,136. (No model.)

To all whom it may concern:

Be it known that I, OLIVER GILTNER, a citizen of the United States, residing at Portland, in the county of Multnomah and State of Oregon, have invented new and useful Improvements in Bolt or Spike Pullers, of which the following is a specification.

This invention relates to improvements in bolt and spike pullers, the prime objects in view being to produce a powerful and efficient device at a reasonable cost and which is adapted to firmly grip the body of a bolt or spike and gradually and with slight labor upon the part of the operator draw the same from heavy timber, and this, too, without bending or otherwise rendering said bolts or spikes unfit for further use as such.

Other objects and advantages of the invention will hereinafter appear, and the novel features thereof will be particularly pointed out in the appended claims.

Referring to the drawings, Figure 1 is a side elevation of a bolt or spike puller embodying my invention, portions being broken away to expose the interior. Fig. 2 is a central section through the upper end of the device. Fig. 3 is a sectional view of the spreader-block, the feed-screw being shown in elevation.

Similar numerals of reference indicate similar parts in all the figures of the drawings.

In practicing my invention I employ a lower base-plate 1 and an upper head-plate 2, both of which are preferably circular. These base and head plates are connected at intervals by standards 3, which serve to space the two plates apart and combines with them to form a strong and rigid frame. These parts are preferably formed of cast-steel and may be integral, if desired. Each of the plates 1 and 2 is provided with a central opening 4, (see dotted lines Fig. 1,) the opening in the plate 1 serving as a passage for the bolt or spike 5 and that in the plate 2 for the feed-screw 6, hereinafter mentioned.

Mounted to rotate on the upper or head plate 2 is a nut 7, provided on its upper side with a raised squared boss or shoulder 8, capable of receiving the head of a wrench 10. This nut is provided with a central opening 9 and within the same is loosely threaded an externally-threaded vertically-disposed feed-

shaft 6, hereinbefore referred to. The shaft is hollow throughout its length and at its lower end may be provided with an annular 55 boss 11, upon which is loosely swiveled a square expanding or spreader head 12, the latter having the boss 11 let therein in a recess 13, formed in its upper side, and likewise provided with a bottom opening 14, corresponding to and forming a continuation of the bore in the feed-shaft.

Pivoted loosely at opposite sides of the spreader 12, as at 15, are depending links 16, each of which is at its lower end pivoted, as 17, to the upper ends of a pair of toggle-links 18, the latter in turn being pivoted, as at 19, to a pair of toggle-jaws 20. The toggle-jaws 20 are curved toward each other at their lower ends, each terminating in a gripping- 70 face 21, and toward their upper ends diverge, being provided with oppositely - inclined wedging faces 22, which take at opposite sides of the spreader 12.

The operation of the invention will be 75 readily apparent and is briefly explained as follows: By manipulating the lever or wrench 10 in one direction the feed-screw 6 may be run down through the nut 7 a sufficient distance to enable the gripping-surfaces 21 of 80 the jaws 20 to clamp or grip the opposite sides of a bolt or spike 5, when the direction of rotation of the wrench being reversed the draft through the links 18 and 16 causes the said jaws to tighten and a further upward 85 movement given the feed-screw to gradually and vertically draw the bolt or spike from the timber. If the bolt or spike is too long to be withdrawn by the limited travel of the screw, the direction of the latter may be again reversed, the upper or exposed portion of the bolt or spike passing upward into and beyond the same, as illustrated in Fig. 1, a new and lower grip taken and the operation repeated as many times as may be found necessary. It will be observed that the action of the jaws in gripping and relaxing is automatic and is the result of feeding the screw either upward or downward.

Having described my invention, what I claim is—

1. In a bolt or spike puller, the combination of a frame having upper and lower heads provided with alining openings, a rotatable

nut seated on the upper head and adapted to receive a wrench, a hollow feed-screw threaded in said nut and located in the upper opening, a head swiveled at the lower end of the screw, 5 opposite pivoted vertical links depending from the head, a pair of gripping-jaws located at opposite sides of the swiveled head and having at their upper ends inclined faces acted upon by the said swiveled head, and 10 toggle-links connected pivotally to the lower ends of said vertical links and at their outer ends to said jaws below the inclined faces of the latter.

2. In a bolt or spike puller, the combination of a frame having upper and lower heads provided with alining openings, a feed-screw located in the upper opening, a head swiveled at the lower end of the screw, opposite pivoted vertical links depending from the 15 head, a pair of gripping-jaws located at opposite sides of the swiveled head and having at their upper ends inclined faces acted upon by the said swiveled head, and toggle-links connected pivotally to the lower ends of said 20 vertical links and at their outer ends to said

jaws below the inclined faces of the latter, and means for rotating the screw in either direction.

3. In a bolt and spike puller, the combination of the upper and lower heads 2 and 1, 30 provided with alining openings 4, the internally threaded and shouldered nut 7, the operating-wrench having head 10 fitting said shouldered nut, the hollow feed-screw 6, terminating at its lower end in the head 11, the 35 square spreader 12, having the recess 13 to receive said head 12, and opening 14, opposite links 16, pivoted at their upper ends as at 15 to the spreader, the curved gripping-jaws 20, terminating in grippers 21, and having the opposite inclined faces 22, and the short toggle-links 18, pivoted as at 17, to the lower ends of links 16, and at their outer ends as at 19 to the jaws 20.

In testimony whereof I affix my signature 45 in presence of two witnesses.

OLIVER GILTNER.
